UNITED STATES PATENT OFFICE

100,869

DESIGN FOR A WATCH CONTAINER

Eugene J. Lux, New York, N. Y.

Application June 30, 1936, Serial No. 63,581

Term of patent 3½ years

To all whom it may concern:—

Be it known that I, Eugene J. Lux, a citizen of Austria, residing at New York city, county of New York, Borough of Manhattan, and State of New York, have invented a new, original, and ornamental Design for a Watch Container, of which the following is a specification, reference being had to the accompanying drawing, forming a part thereof.

Figure 1 is a top plan view of a watch container showing my new design.

Figure 2 is a front elevation of Figure 1.

Figure 3 is a rear elevation of Figure 1.

Figure 4 is an end view of Figure 1.

I claim:

The ornamental design for a watch container, as shown.

EUGENE J. LUX.
